UNITED STATES PATENT OFFICE.

PAOLO CORVAJA, OF PALERMO, SICILY, ITALY.

BALLASTING SHIPS IN PORT.

SPECIFICATION forming part of Letters Patent No. 225,800, dated March 23, 1880.

Application filed September 6, 1879.

To all whom it may concern:

Be it known that I, PAOLO CORVAJA, of Palermo, Island of Sicily, Kingdom of Italy, have invented a new and useful Improvement 5 in Ballasting Ships in Port, of which the following is a specification.

My invention relates to improvements in the method and apparatus for ballasting ships in port.

10 The present mode of outside ballasting consists in hanging logs of wood by chains or ropes from the sides of the vessel as counter-balancing weights, so that when the vessel attempts to keel over from any cause while lying 15 at the wharf or being towed the weight of the log on the higher side alone prevents her from doing so, for on the lower side the slackening of the chains or ropes lets the log on this side float in the water; hence it is of no use, 20 and the strain of righting the vessel is thrown entirely on one side. Also, this arrangement fails in its purpose of keeping the vessel steady, as when she rolls the log sinking in the water relieves her of its weight, whereby an un- 25 steady motion is maintained; further, as the logs are not rigidly connected with the ship, they are apt to chafe her sides.

Now, the object of my invention is to temporarily ballast ships by the weight and buoyancy of the ballasting-logs, combined; and it consists, first, in the method of ballasting by the weight and buoyancy of the logs; and, secondly, in the construction and arrangement of the logs for the purpose of ballasting the 35 vessel in this way.

In the accompanying drawings, Figure 1 is a side elevation of a vessel's hull provided with my improved ballasting apparatus. Fig. 2 is a cross-sectional elevation of the same 40 on line $\alpha\alpha$ of Fig. 1. Fig. 3 is a detail view of the suspension-rod for the logs; and Fig. 4 represents a modified form of device for connecting the suspension-rods with the spar.

Similar letters of reference indicate corresponding parts.

Referring to the drawings, A is the hull of the vessel, B is the deck, and C C are the bulwarks. Across the deck are laid, and secured against turning, spars D D, with their ends 45 projecting through openings in the bulwarks and sufficiently far beyond to insure the sides

of the vessel from contact with the suspension-rods E pendent from the ends of the spars.

The suspension-rods E are composed of two sections—an upper one, a , and a lower one, a' , 55 the two being connected together by a screw-threaded sleeve, b , engaging the screw-threaded ends of the rods, as clearly shown in detail in Fig. 3. The object of this construction of the suspension-rods is to enable them to be lengthened or shortened, as may be necessary, to adjust them to the draft of the vessel. Instead of rods a a' and sleeve b , any other suitable device or connection for adjusting the 60 lengths of suspension-rods E may be employed. 65

The upper ends of the suspension-rods E are pivoted to the ends of the spars D, so that the said rods E may swing freely in the direction of the length of the vessel, but are held rigidly against any lateral movement, to 70 prevent their striking against or coming in contact with the vessel's sides. This pivotal connection between the rods E and spars D is made in several different ways. One connection may consist of a ring, b' , placed over 75 the end of the spar and secured thereto against turning. From its under side depends a link or coupling, c , to which the upper end of section a is pivoted. Another pivotal connection consists of a plate, d , attached to the 80 under side of the spar, from which depends a link, d' , or coupling, to which the end of rod E is pivoted. Still another pivotal connection consists of a link, e , or coupling, with a screw-bolt, e' , which is passed up through the 85 end of the spar from the under side, and secured in place by a burr, the rod E being pivoted as before. Another arrangement for the pivotal connection is composed of a coupling, f , on the end of a shank, g , which is driven 90 into the end of the spar D, the rod E being pivoted to the coupling, as shown in Fig. 3. The last form of pivotal connection is shown in Fig. 4, and it consists of a collar, h , on the 95 end of rod E, which is passed over the end of the spar, and confined between cleats i i , so as to turn freely on the spar as a pivot when the rod E is swung.

The lower end of rod E is forked, and attached by hooks and eyebolts k l , screwed into 100 the logs, or attached by other suitable fastenings to the logs D, or by sinking the ends of

the branches into the logs and securing them by pivots, as at *n* in Fig. 1.

By the pivotal connection of the suspension-
5 rods *E* with the spars *D* the logs *F* are per-
mitted to swing freely in the direction of the
length of the vessel, or in a plane parallel to
but at a proper distance from the sides of the
vessel, to prevent contact therewith. At the
10 same time the pivotal connection between the
suspension-rods *E* and the logs *F* permits the
former to turn freely on their pivotal connec-
tions when moved lengthwise without affect-
ing the logs, which maintain a position par-
15 parallel to the water, and thus are always in a
position to buoy up the vessel when they are
in the water.

The ballasting-logs *F* are of the general form
of a boat, with a very great length in propor-
tion to their breadth. Their sides are either
20 tapered to the bottom, like a boat, or stepped,
the two forms being shown clearly in
Fig. 2.

By means of ropes *G* *G'* the ends of the
logs are connected with the bow and stern, re-
25 spectively, of the vessel, as shown in Fig. 1. The
purpose of this arrangement is to limit the
swing of the logs lengthwise.

The operation of the invention is as follows:
When the vessel is loaded and the ballasting-
30 logs *F* are applied, the ropes at one end—say
G, at the stern—are slackened. This permits
the logs to swing forward and, of course, up-
ward, as indicated by the dotted lines in Fig.
1, and thus accommodate themselves to the
35 draft of the vessel. As the cargo is discharged
and the vessel lightened the logs *F* swing
back, the slackened ropes *G* *G'* being tight-
ened as the suspension-rods *E* approach a per-
pendicular position. As the vessel rises she
40 bears through the suspension-rods *E* on the
logs *F* at her two sides; and the logs being
held from moving off sidewise by the manner
of connecting the suspension-rods *E* with the
spars, and from lengthwise movement by the
45 ropes *G* *G'*, they sustain the two sides of the
vessel by their buoyancy, and thus ballast her
and keep her steady.

If, from any cause whatever, the ship
50 careens, the log on the rising side acts as a weight
or counter-balance, while the log on the lower-
ing side sustains this side by its buoyancy, the
weight of one log and the buoyancy of the

other co-operating to ballast and steady the
vessel. This co-operation is brought about by
the adjustment of the logs *F* being such that
55 when the vessel is perfectly ballasted the logs
are equally in the water and ballast her by
buoying up her two sides; but as soon as the
vessel careens, either by her instability or by
the force of the wind, or from other cause, the
60 log *F* on the side that rises is lifted, and its
weight, instead of being sustained by the water,
is thrown on the ship, with the effect of resist-
ing her movement and drawing her back,
while the downward movement of the vessel
65 on the other side is resisted by the buoyancy
of the log *F* on the lower side. Thus the two
logs co-operate, one by its weight and the other
by its buoyancy, to arrest the careening of the
70 ship.

My method of ballasting by the combined
weight and buoyancy of the logs enables me,
in cases where the instability of the ship is not
too great, to employ a single log with safety.
This is done by suspending one of the logs
75 from a spar of sufficient length to yield ample
leverage, so that the log will rest on the water
and ballast the vessel perfectly, both as a
counter-balance and buoy in itself at the same
time.

By availing myself of the combined buoyancy
and weight of the logs much smaller logs may
be employed; and where the ship has room,
so that the length of the spars to which the
logs are hung can be increased without incon-
venience, very small logs will answer the pur-
pose on account of the leverage obtained.

Having thus described my invention, I claim
as new and desire to secure by Letters Pat-
ent—

In ballasting ships in port, the combination
of the inflexible rods *E* with the logs *F*, spars
80 *D*, and ropes *G* *G'*, substantially as herein
shown and described, whereby the said logs
are adapted to be adjusted and held in posi-
tion for ballasting and steadyng the ship,
either by their buoyancy alone or by the buoy-
ancy of one and the weight of the other co-
operating together.

PAOLO CORVAJA.
